UNITED STATES PATENT OFFICE.

VICTOR E. SUMMERS, OF PITTSBURGH, PENNSYLVANIA, ASSIGNOR TO HOLMES ELECTRIC PROTECTIVE COMPANY, OF NEW YORK, N. Y., A CORPORATION OF NEW YORK.

FLEXIBLE CONNECTING DEVICE FOR ELECTRICAL CIRCUITS.

Application filed September 3, 1921. Serial No. 498,873.

To all whom it may concern:

Be it known that I, VICTOR E. SUMMERS, a citizen of the United States, residing at Pittsburgh, in the county of Allegheny, 5 State of Pennsylvania, have invented certain new and useful Improvements in Flexible Connecting Devices for Electrical Circuits, of which the following is a full, clear, concise, and exact description.

10 This invention relates to a flexible device for connecting and preserving the continuity of two sections of an electrical circuit which may be affixed to two separate objects.

15 The primary object of the invention is to provide a permanent electrical connection between two points, which will not be disturbed by the relative movements of the points due to the vibrations of either of 20 them and which can not be easily disturbed by other mechanical interferences.

The connecting device of this invention is particularly adapted for use in burglar 25 alarm circuits of the type wherein an alarm circuit may be included in a tinfoil stripping affixed to a window pane, the circuit being continued from the tinfoil stripping to an exterior alarm circuit, any break in the circuit in the tinfoil caused by tampering with the window pane causing the actuation of alarm devices in the exterior 30 circuit. It has been the practice in connecting together the tinfoil stripping and the exterior alarm circuit, which might be 35 mounted on the window sash, to solder the wire or conductor of the exterior alarm circuit directly to the tinfoil. This formed a rigid and fixed connection that might give satisfactory service if the window pane and 40 sash were firmly fastened together. However, if the pane of glass should work slightly loose from the sash, this type of connection might easily become broken. This result might occur from various causes 45 such as the rattling of the pane due to the wind or to pressure exerted on the pane during the process of washing it. Accordingly, it is a feature of the invention to obviate the above described difficulties, and 50 to provide a connecting device which will possess a flexible characteristic so that, in the event that the two objects upon which the circuits are mounted are not rigidly and firmly fixed together, the continuity of

the circuit will be protected and preserved. 55

Another feature of the invention resides in a cup-shaped container which encloses the flexible conductor and which protects it from external mechanical interferences which might tend to break the connection. 60

While the connecting device of this invention is particularly adaptable for a burglar alarm circuit of the type referred to, it is equally well adapted for use in connecting together other types of circuits in other situations. Further features and objects of the invention will appear more fully from the detailed description thereof hereinafter given.

The invention may be more fully understood from the following description, together with the accompanying drawings which illustrate a preferred embodiment thereof, and in which,

Fig. 1 shows the device interconnecting portions of an alarm circuit which are attached to the frame or sash of a window and a tinfoil stripping mounted on the pane.

Fig. 2 is an enlarged sectional view of the connecting device in position.

Fig. 3 is an enlarged perspective view showing the rear of the device.

Similar reference characters have been utilized to denote like parts in all of the figures.

Referring now to the drawings in detail, a pair of connecting devices 5 are shown mounted upon a window frame 6, and interconnecting tinfoil stripping 7 attached to a pane of glass 8 and conductors 9, included 85 in an alarm circuit.

Each of the connectors comprises a plate portion 10 of rectangular shape constructed of copper or other suitable conducting material, one end of which is reduced to form 95 a tongue 11, the outer end of which is rounded and stamped outwardly to form a cup-shape portion 12. Two rectangular sheets of insulating material 13 and 14 are mounted on opposite sides of the plate portion 10, an eyelet 15 passing through registering openings in the insulating sheets 13 and 14, and an opening 16 formed in the plate portion 10 serving to clamp the insulating sheets and the plate portion together, lugs 17 integral with the plate portion 10 serving to prevent the insulating sheet 14 from moving. The opening 16 in

the plate portion 10 is of larger diameter than the openings in the insulating sheets 13 and 14 and when the eyelet is clinched in position, one flange 25 thereof is depressed far enough to force the adjacent edges of the insulating sheet 13 through the opening 16 in the plate portion 10, which serves both to completely insulate the plate portion 10 from the eyelet and at the same time to render the edge of the flange 17 flush with the outer surface of the insulating sheet 13, as is shown in Fig. 2.

In applying the connector to a window, the tongue portion 11 is bent to assume the proper angle to allow the sheet 13 of insulating material to lie flat against the window frame and the edge 18 of the cup-shape member 12 to lie flat against the window pane. The connector is held in place by means of a screw 19 which is inserted through the eyelet 15 and secured in the window frame 6. Since the eyelet 15 is completely insulated from the flat portion 10, which is of conducting material, the connector may be applied to window frames which are constructed of metal.

The upper edge of the plate portion 10 is bent at the point 20, as shown in Fig. 2, in order to space it from the sheet 13 a distance to provide room in which to solder the ends of conductors 9 which, as previously explained, are included in an alarm circuit. The foil stripping 7 is electrically connected with the connector by means of a wire 24 soldered thereto, which projects through an arcuate slot 21 cut in the lower periphery of the cup-shape portion 12. The wire 24 is looped to form a coil 22 which is housed within the cup-shape portion 12, the other end 23 of the wire being soldered in a triangular depression communicating with the cup-shape portion 12 and formed at a point diametrically opposite the arcuate slot 21.

By referring to Figs. 1 and 2, it will be seen that the electrical circuit may be traced from one conductor 9, plate portion 10, tongue 11, cup-shape portion 12, wire 24 to the foil stripping 7, thence through the stripping to another connector which is connected both to the stripping and to another conductor 9 of the alarm circuit.

Due to the presence of the slot 21, clearance is afforded the wire 24 to permit it to be moved from side to side in the event that the window pane should be moved in a substantially horizontal direction relative to the window frame, and due to the coil 22 the window pane may move in a substantially vertical direction relative to the frame or away from the frame, causing an elongation of the wire 24. Due to the manner in which wire 24 is mounted, the pane 8 may move in any direction relative to the frame without causing any breaking of the connec-

tion between the stripping and the cup-shape portion of the connector.

The coil 22 is housed within the cup-shape portion 12 in order to shield it from outside mechanical interferences such as might occur for instance when the pane of glass is washed.

With a device of this character the continuity of the electrical circuit is less apt to be disturbed unnecessarily than in former arrangements. While the device is particularly useful in its application as herein specifically pointed out, it is understood that it may be used for connecting together portions of other types of electrical circuits, and while it has been disclosed in certain arrangements which are deemed desirable, it is understood that it is capable of embodiment in many and widely varied forms other than those disclosed.

What is claimed is:

1. A device for interconnecting two electrical circuits, said device comprising a body member, the upper portion thereof being adapted for connection with one electrical circuit, the lower portion thereof being of concave shape, and a conductor attached to said lower portion and being coiled within said concave portion, said conductor being adapted to be connected to the other electrical circuit.

2. A device for interconnecting two electrical circuits, said device comprising a body member, the upper portion thereof being adapted for connection with one electrical circuit, the lower portion thereof being of concave shape, and a conductor flexibly mounted on said body member within said concave portion, and adapted to be connected to the other electrical circuit.

3. A device for interconnecting two electrical circuits, said device comprising a body member, the upper portion thereof being adapted for connection with one electrical circuit, the lower portion thereof being of concave shape, a conductor flexibly mounted on said body member within said concave portion and adapted to be connected to the other electrical circuit, and insulating strips covering the upper portion of said body member.

4. A device for interconnecting two electrical circuits, said device comprising a body member, the upper portion thereof being adapted for connection with one electrical circuit, the lower portion thereof being of concave shape, a conductor flexibly mounted on said body member within said concave portion and adapted to be connected to the other electrical circuit, insulating strips covering the upper portion of said body member, said insulating strips and said upper portion of said body member having an opening therethrough, the opening in said body member being larger than the opening

in said insulating strips, and an eyelet affixed to said insulating strips in said opening.

5. A device for interconnecting two electrical circuits, said device comprising a body member, said body member reduced to form a tongue having the lower portion of said tongue of concave shape, the body portion being adapted for connection with one electrical circuit, and a conductor flexibly mounted on said tongue and within said concave portion, and adapted to be connected to the other electrical circuit.
- 10

6. A device for connecting two electrical circuits, said device comprising a body portion, insulating strips covering said body portion, a tongue integral with said body portion and projecting beyond said insulated strips, the lower portion of said tongue being of concave shape, and a conductor 20 flexibly mounted on said tongue and within said concave portion.

In witness whereof, I hereunto subscribe my name this 29th day of August, A. D. 1921.

VICTOR E. SUMMERS.
